CLAIM

The ornamental design for a bottle cap as shown and described.

DESCRIPTION

FIG. 1 is a perspective view of a bottle cap showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is another perspective view thereof shown with handle lifted in a configuration of use; and,

FIG. 10 is another perspective view thereof shown with handle lowered and cap opened in an alternate configuration of use.

The broken lines in the drawings depict portions of the bottle cap that form no part of the claimed design.
